5 Claims. (Cl. 155—179)

This invention relates to seats, especially of the type adapted for use in motor vehicles, and it is an object of the present invention to provide a seat which is very low in manufacturing cost and at the same time provides a comfortable and durable product.

Another object of the invention is to provide a seat, the base of which is constructed of a material to which the upholstery fabric can be readily attached, as by stapling, sewing, gluing, or the like.

It is another object of the invention to utilize such a base material and to so construct the base that it will interlock with said supporting members, such as longitudinal beams.

Another object is to provide simple, inexpensive attaching means for fastening the seat in place upon its supports.

Other objects will appear from the following description of an illustrative embodiment of the invention taken together with the attached drawings wherein:

Fig. 1 is a transverse cross-section through a seat embodying the invention and through the longitudinal seat supports;

Fig. 2 is a detail cross-sectional view taken on the line II—II of Fig. 1;

Fig. 3 is a detail cross-sectional view taken on the line III—III of Fig. 1;

Fig. 4 is a partial cross-sectional view similar to Fig. 3, taken along the line IV—IV of Fig. 5, drawn to a larger scale and illustrating a modified construction; and

Fig. 5 is a top plan view of the modified construction illustrated in Fig. 4.

Referring to said drawings, the numeral 1 indicates the base of the seat which, for reasons which will become apparent, is constructed of a material which may be formed to shape, which is readily perforable (for the reception of wire staples, for sewing, etc.), and to which preferably glue and other adhesives will readily adhere. Among the materials contemplated are fibre, cardboard, imitation leather, "Pertinax," etc. "Pertinax," as is commonly known, consists of fibrous material such as paper, impregnated with an artificial resin such as phenol formaldehyde, forming a hard, strong but easily formed material which will retain its shape and is easily perforated. As seen in Fig. 1, the ends 2 and 3 of the seat base 1 have been bent upwardly, outwardly, and downwardly, so that in use these end portions serve to fit over the seat supporting members 4 and 5 which are preferably longitudinally extending tubular members,

as shown. The upholstery fabric 7 of the cushion, which may be otherwise of usual construction, has its edges 8 and 9 folded around the downwardly extending edges 2 and 3 of the cushion base and are attached thereto, as shown, by means of a series of staples 10, as is shown clearly in Fig. 2.

As shown in Fig. 3, the forward edge and also the rear edge (not shown) of the cushion base 1 is also bent upwardly and then downwardly to increase the rigidity and strength of the base and to provide the downwardly extending edge 14 around which the edges 15 of the upholstery 7 may be folded and preferably attached, as by staples 10.

It will be noted that the base member is originally sheet material which, by the use of a suitable form, and the application of heat, if necessary, is formed or molded to the shape shown 20 which, on account of its construction, provides a stiff and rigid base even though the material itself may be rather thin, which base will adequately serve as a support for springs S of any usual or suitable construction. Said springs support at their upper ends the usual padding P.

In view of the unique characteristics of the cushion base material which permits of its being formed or molded to any desirable shape, numerous modifications of the invention are possible. 30 Thus, for example, the bottom portion 16 of the cushion base itself may be formed wavy or corrugated and in some cases strengthened through a sheet of cardboard or fibre, such as illustrated by the V-shaped sheet material 17 of Fig. 3, or the 35 strengthening element may consist of thin sheet metal, in which case, the flange thereof might be slit, with tabs bent up therefrom, which tabs would then, upon application of the reinforcing material to the cushion base, penetrate it and 40 then be clinched over. Such a construction is illustrated in Figs. 4 and 5, showing thin metal strengthening members 18 having split flanges one of which 19 extends through suitable openings in the bottom portion 16 of the cushion base and is then bent over to hold the strengthening members in place. However, sewing of the edge 45 of the cushion base would also come into consideration. All these special forms are immaterial, which is of course also true of the materials used for upholstering and also how the seat frame is built.

The invention is not only applicable to cushions for power vehicles but to cushions of all types whether as seat cushions alone, or whether

as cushion backs, or in some cases also as arm cushions.

The word "fibre" as applied to the material of which the base is formed as used in this specification is intended to include any material which may be formed to shape by bending and pressing and which at the same time is sufficiently perforable for the reception of wire staples, or for sewing, or the like.

In the left half of Fig. 1, means are shown for fastening the seat upon the seat supports. This occurs through a plurality of clips 11 formed of spring steel one end portion 12 of which is passed through an aperture in the seat base 1 and bent over, and whose other end 13 is preferably split and is received in a slit in the seat support 4 or 5, thus serving to hold the seat cushion down in place upon its supports.

It will be noted that the construction shown and described will serve admirably to accomplish the objects stated above. It is to be understood, however, that the construction disclosed above is intended merely as illustrative of the invention and not as limiting as various modifications therein may be made without departing from the invention as defined by a proper interpretation of the claims which follow.

I claim:

1. In a seat structure, especially for motor vehicles and adapted to rest upon spaced seat supporting members, comprising a base member, resilient means supported by said base member, and upholstery surrounding said resilient means, said base member being formed of fibre formed to such a shape that the end portions thereof extend over said seat supports and then downwardly, said upholstery being extended downwardly under and folded upwardly over the said downwardly extending portions of said base member, and then directly attached thereto.

2. In a seat structure, especially for motor vehicles, comprising a base member, resilient means supported by said base member, a strengthening member of sheet material attached at spaced points to said base member, the intermediate portions of said strengthening member being bent away from said base member, and upholstery surrounding said resilient means, said base member consisting of fibrous material impregnated with artificial resin pressed in such a shape that the end portions thereof extend downwardly, said upholstery being extended downwardly under and folded upwardly over the said downwardly extending portions of said base member, and then directly attached thereto.

3. In a seat structure according to claim 1 in which the seat is attached to said seat supporting members by means which pass through apertures in the base and in the supporting members.

4. In a seat structure, in combination, a base member formed of hard, impregnated fibrous material having downwardly formed edges, a plurality of substantially V-shaped sheet strengthening members for said base member, the ends of the legs of said V-shaped member being outwardly flanged, means for attaching said V-shaped members to said base member through said flanges, resilient means supported by said base member, upholstery surrounding said resilient means, and means for attaching said upholstery to the downwardly formed edges of said base member.

5. The combination according to claim 4, in which said strengthening members consist of sheets of pasteboard, and said first named attaching means are staples extending through said strengthening members and base member.
